UNITED STATES PATENT OFFICE.

HOWARD E. SNYDER, OF BOMANSTOWN, PENNSYLVANIA.

STEP-BOX.

SPECIFICATION forming part of Letters Patent No. 593,695, dated November 16, 1897.

Application filed December 12, 1896. Serial No. 615,512. (No model.)

To all whom it may concern:

Be it known that I, HOWARD E. SNYDER, a citizen of the United States, residing at Bomanstown, in the county of Carbon and State of Pennsylvania, have invented certain new and useful Improvements in Step-Boxes; and I do hereby declare the following to be a full, clear, and exact description of the invention, such as will enable others skilled in the art to which it appertains to make and use the same.

This invention relates to improvements in bearings, and has more particular relation to step-box bearings.

The invention consists of certain other novel constructions, combinations, and arrangements of parts, all of which will be hereinafter more fully described and claimed.

In the accompanying drawings, forming part of this specification, Figure 1 represents a central vertical section through a step-box embodying my invention. Fig. 2 represents an enlarged detail perspective view of the step-box proper. Fig. 3 represents an enlarged detail perspective view of the journal-ring, and Fig. 4 represents an enlarged detail perspective view of the shaft.

A in the drawings represents the frame or casing; B, the step-box proper; C, the journal sleeve or ring; D, the shaft, and E the feather or key. Said casing or frame A is preferably cylindrical in form and is closed at its lower end, as at a, and provided at its upper end with an annular flange a', whereby it may be suitably mounted in the frame of the crusher or other machine to which the step-box is to be applied. The step-box proper, B, is of such diameter as to fit snugly within the casing A and is formed with a socket b, having an upwardly-projecting stud b' arranged in its bottom. Antifriction-balls b² are adapted to be applied in said socket about said upwardly-projecting stud. The diameter of the socket in said step-box is slightly greater than the diameter of the lower journal end of the shaft D. The journal-sleeve C is of such diameter as to fit snugly within the frame A and is provided with a central aperture c, through which the journal portion of the shaft D is adapted to pass, whereby a lateral support for said shaft is provided. This ring C is provided with a plurality

of vertical oil-passages c', adapted to correspond in position with inclined oil-channels b³, formed in the upper surface of the box B, whereby oil may be introduced into the socket of said box. The casing A is provided with a suitable key or feather groove a², adapted to receive the headed key or feather E. The said box B and ring C are provided, respectively, with similar feather-grooves b⁴ and c⁴, adapted to receive said feather E. The said shaft D is adapted to be passed down through the opening in the bearing-ring C, so that its lower end will rest firmly upon the antifriction-balls mounted in the socket of the step-box. The lower end of said shaft D is made slightly conical, so as to normally force the antifriction-balls out away from the central stud mounted in the socket of the step-box.

It will be observed from the foregoing description that the shaft D is supported in my improved step-box upon antifriction-rollers which prevent all heating and cutting of the lower end of the shaft and permit of its running free with a minimum amount of friction. The heating and cutting of the shaft are further obviated by the peculiar construction of the oil-passages for the socketed step-box. These passages permit of the said step-box being filled or stored with oil, so that the lower end of the shaft always operates directly in the oil, where it cannot become heated.

The parts of this device are very simple and cheap in construction, and, being removable, may be readily replaced, should they become worn, by simply removing the feather E and the step-box and bearing-ring.

This invention is intended principally for application to the shafts of heavy machinery—such as mills, stone-crushers, and the like—in which the vertical operating-shafts are caused to support a great many tons.

Having thus described my invention, what I claim as new, and desire to secure by Letters Patent, is—

1. In a step-box, the combination with a supporting-frame, of a socketed step-box proper mounted therein and provided with a centrally-located stud in its bottom, antifriction-balls of a greater diameter than the height of the stud and applied in said step-box about said stud, and a shaft having a

lower conical end adapted to engage said balls to force them out away from the stud, substantially as described.

2. In a step-box, the combination with a suitable supporting-frame, of a socketed step-box mounted therein and provided with a peripheral vertical groove, a supporting-ring also mounted in said frame above said step-box and provided with a similar peripheral groove, a key for locking said ring and box firmly together, antifriction-balls mounted in

1 said box, and a shaft adapted to have its lower ends supported by said balls, substantially as described.

In testimony whereof I have signed this 15 specification in the presence of two subscribing witnesses.

HOWARD E. SNYDER.
